Primary Examiner — Mehri F Bajoul(74) *Attorney, Agent, or Firm* — Thorpe North & Western, LLP(57) **CLAIM**

The ornamental design for the cornhole board as shown.

DESCRIPTION

FIG. 1 is a top perspective view of the cornhole board in accordance with my invention, shown in an unfolded configuration;

FIG. 2 is a bottom perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof;

FIG. 8 is a right side elevation view thereof; and,

FIG. 9 is a perspective view thereof, shown in a folded configuration.

The broken lines shown in the drawings depict portions of the cornhole board that form no part of the claimed design.

1 Claim, 8 Drawing Sheets(56)
